Fig. 1.

Fig. 2.

Fig. 3.

Fig. 4.

Fig. 5.

Fig. 6.

Fig. 7.

Fig. 8.

FIG. 1 is a perspective view of a hand held shower spray head showing our new design;

FIG. 2 is a side elevational view of same taken from the side opposite that seen in FIG. 1;

FIG. 3 is a side elevational view of same taken from the right of FIG. 2;

FIG. 4 is a side elevational view of same taken from the left of FIG. 2;

FIG. 5 is a top plan view of same;

FIG. 6 is a bottom plan view of same;

FIG. 7 is a fragmentary perspective view of a modified form of the hand held shower spray head shown in FIG. 1, the omitted body portion being the same as that shown in FIG. 1; and

FIG. 8 is a top plan view of FIG. 7.

We claim:

The ornamental design for a hand held shower spray head, as shown and described.
